JACK-IN-THE-BOX TOY

Robert K. Ostrander, Rolling Meadows, Ill., assignor to
The Quaker Oats Company, Chicago, Ill.

Filed Mar. 3, 1971, Ser. No. 120,792

Term of patent 14 years

Int. Cl. D21—01

U.S. Cl. D34—15

FIG. 1

FIG. 2

FIG. 3

FIG. 4

FIG. 5

FIG. 6

FIG. 1 is a front elevation of a jack-in-the-box toy showing my new design;

FIG. 2 is a side elevation thereof as viewed from the left in FIG. 1;

FIG. 3 is a rear elevation thereof;

FIG. 4 is a top plan view;

FIG. 5 is a front perspective view with the cover open; and

FIG. 6 is a rear perspective view of the toy as shown in FIG. 5 with the cover open.

I claim:

The ornamental design for a jack-in-the-box toy, substantially as shown.
